ULTRA HIGH FREQUENCY GENERATOR

Ernest C. Okress, Montclair, N. J., assignor to
Westinghouse Electric Corporation, East Pittsburgh, Pa., a corporation of Pennsylvania

Application February 17, 1945, Serial No. 578,372

12 Claims. (Cl. 315—40)

1

This invention relates to ultra high frequency generators and more particularly to the type generally known as magnetrons.

Magnetrons are more commonly of fixed or monochromatic wave length. Small variations in the applied fields will alter the frequency slightly but such meager variations are inadequate for tuning purposes. It is highly desirable to provide a magnetron the wave length of which is capable of being suitably varied at will. It is furthermore desirable to provide a single control for operator manipulation to effect the tuning and to use a control requiring minimum attention and effort to operate and which will remain fixed until the operator makes a further adjustment thereof. It is an advantageous feature to have an almost proportionate change in wave length with the mechanical change of the adjustable part, that is, as near linear as possible. For a given output, as small an overall size of device as possible is wanted. It is sought to have a magnetron that will operate at as low a voltage as possible for desired output and to maintain this voltage over the complete tuning range of the tube. Provision of a magnetron and tuning means as part thereof which are "fool proof" and of a character which will not readily become damaged in use nor have possibility of endangering the operator using the same. Also, it is desirable to have a magnetron operate in as low a magnetic field as possible so as to reduce the mass to a minimum.

In its general aspect, therefore, the invention has for its objects the accomplishment of the several desiderata given above.

More specifically, the invention is directed to the accomplishment of the desiderata enumerated by specific arrangement, construction and relationship of parts herein shown and described.

These and further objects of the invention will appear to those skilled in the art to which the invention appertains as the description proceeds, both by direct recitation thereof and by implication from the context.

Referring to the accompanying drawings in which like numerals of reference indicate similar parts throughout the several views;

Figure 1 is a view looking at the output end of a magnetron embodying my invention;

Figure 2 is a plan looking in the direction of the arrows shown in conjunction with line III—III of Fig. 1;

Figure 3 is an enlarged sectional view on line III—III of Fig. 1;

Figure 4 is a section on line IV—IV of Fig. 2;

2

Figures 5 and 6 are sectional views on lines V—V and VI—VI respectively of Fig. 3;

Figure 7 is a longitudinal sectional view of the cathode;

Figure 8 is a plan of the anode shell with cover plate removed and showing the vanes and cavities therein as well as the straps at the near ends of the vanes;

Figure 9 is a perspective view of broken away portions of the vanes at the parts thereof prepared for strapping; and

Figure 10 is a perspective view showing relation of the magnetron straps in use.

In the specific embodiment of the invention illustrated in said drawings, the reference numeral 10 designates the body portion, known as the anode, of the magnetron. This anode is composed primarily of a vane structure such as shown in applications Serial No. 460,376, filed October 1, 1942, now U. S. Patent No. 2,520,955, granted September 5, 1950, and Serial No. 462,132, filed October 13, 1942, and both assigned to the same assignee as the present application. Said anode is comprised of a substantially cylindrical metallic shell within which are partitions or radial vanes 11 projecting from the shell inwardly to a central cathode chamber or interaction space 12. These vanes form a circular series of trapezoidal or "pie shaped" cavities 13 having longitudinal apertures 14 which open into the interaction space 12. The vanes are of less length in direction parallel to the axis than the length of the shell so that end chambers 15 are formed in the shell in the regions beyond the ends of the vanes and closed by end covers 16 which overlie the ends of the shell and which are vacuum sealed thereto. The cavities 13 between the vanes open into the end chambers 15. These end chambers provide a means for electro-magnetic coupling between the cavities 13 to permit oscillation of the tube in its principal mode which is known in the art as the π mode of the first multiple.

At the ends of the vanes 11 and adjacent the interaction space 12 are provided at each end of the anode double ring straps, identified as outer or larger ring 11a and inner or smaller ring 11b. The purpose of these rings is to achieve large mode separation between the desired or π mode and the lower order modes, and destruction of these lower orders. Said destruction of the lower orders of modes is accomplished by the use of breaks in certain straps. For instance, in Figures 4, 8 and 10 strap break 11a is provided in the upper larger strap 11a, whereas strap break 11b is made in lower inner strap 11b. The breaks

are positioned at 90° apart. It will also be noted that the vanes are notched or stepped for reception or passage of the straps, and that the straps each alternate in engagement with the vanes and that vanes engaged by one strap of the pair at one end of the anode are skipped by the other strap of the pair, as can be readily understood from inspection of the step arrangement for the straps in Figure 9 and from the cross section of steps and straps in Figure 4. End chambers or interaction space 12 obtains coupling of the fields of the several cavities 13 so they act as if they were a single cavity, and tight coupling thereof is further promoted and assured by provision of the said straps.

Into the covers, coaxial therewith, are sealed the ends of ferro-magnetic pole pieces 18' of a horseshoe magnet 18 which establish the required magnetic field for proper operation of the magnetron. The pole pieces 18' are coupled to the magnet 18 by means of pole shoes 19 which are split as shown to provide a rotatable engagement on the pole pieces without materially changing the reluctance of the magnetic circuit. The magnet 18 is anchored in proper position and orientation by a lag screw 20 which passes through the middle of the magnet and terminates in a stud 21 on the magnetron shell in a hole provided for the purpose. The stud is vacuum sealed to the shell.

The magnetron anode 10 is provided with an output coupling device 22 vacuum sealed thereto and which couples the line to the magnetron by means of coupling loop 23 in one of the cavities 13. The said device 22 is coupled to a coaxial line (not shown) by a mechanical coupler 24a. It will be noted that the output device with its center conductor a continuation of loop 23 and outer conductor 24 coaxial therewith and connecting between the anode body and said coupler 24a, constitutes a coaxial line. The electromagnetic energy from the magnetron passes through the low loss glass seal 25 of the output device 22 into the coaxial line system.

The feed for the cathode is obtained as usual by cathode leads 26 vacuum sealed through and insulated from the shell of the magnetron anode. The leads of the cathode structure are terminated by non-magnetic metallic links 27 which support the cathode structure. One link 27, shown as the upper one in the drawings, connects with the filament 28 of the cathode 29 by an eyelet arrangement, and the other link connects to both the cathode sleeve 29 and the associated end of filament 28. The outside of said cathode sleeve is of course made to be electron emissive.

The cathode 29 is terminated at each end by a non-magnetic metallic hat or disk 30, here shown as of washer shape. The filament 28 is terminated at one end in an eyelet projecting from hat 30 and is therefore directly connected thereby to the cathode sleeve 29. At its other end, the filament is insulated from the hat thereat to thus avoid short circuiting the filament. For this purpose an insulating bushing 31 is seated in the end of the cathode sleeve with a shoulder portion beyond the end and separating the link and hat by being interposed therebetween and separating the filament and cathode sleeve as well. The end portions of the filament are straight and axially aligned and situated in long eyelets 32. The lower one of these eyelets is secured to the lower one of the hats, whereas the upper one of the eyelets passes through the insulating bushing 31 and is kept free of contact

thereby from the hat. A shorter eyelet 33 is applied or telescoped over the long eyelet and spot welded thereto and in engagement with the bushing at this end of the cathode, and it is to this eyelet that the link 27 for that end of the cathode is attached. Insulating bushing 31 may be peripherally grooved and the sleeve held thereto by crimping it into the groove.

Projecting from the anode body is a tuner assembly 34 here shown as diametrically opposite from the output. This tuner assembly is comprised of a vacuum sealed coupling device 35 having a coupling loop 36 of an area and contour which almost occupies the maximum area and shape of the cavity 13 into which introduced, in order to keep the loaded Q at a desirable minimum. This coupling device has a glass seal 35a between its center conductor 37 and outer conductor 38. The coupling device constitutes a coaxial line, and is connected to the tuner which also constitutes a coaxial line system with outer and inner conductors 39, 40, but which is capable of providing various impedances to the magnetron 10 by means of coupling device 35.

25 The variable reactance, which is of course part of the impedance, is obtained by varying the length of the tuner by means of a movable piston 41 situated in the outer conductor 40. The piston has two inverted coaxial quarter wave lines 42 and 43 which provide at their ends at the gaps 44 and 45, a very high impedance. This high impedance is reflected as a virtual electrical short circuit at gaps 46, 47 at a quarter wave distance from the first said gaps 44 and 45.

35 The piston is composed of a head 48 to which is attached a cylindrical sleeve 49 which supports and generates the two coaxial shorted lines 42, 43 in conjunction with coaxial sleeves 50 and 51 terminating away from the piston head in a transverse cap 52. The cap 52 is spaced far enough from head 48 to provide both for the quarter wave length of sleeves 50, 51 and for intercommunicating spaces 53, 54 between ends of the said sleeves and said head. The spacing 55, 56 between sleeves 50, 51 and the outer and inner conductors respectively are made as small as possible in order to reduce the voltage drop between these sleeves and conductors. Spacing 55 between the outer sleeve and outer conductor provides aforementioned gaps 44 and 46 at the far and near ends thereof respectively, and spacing 56 between the inner sleeve and inner conductor provides aforementioned gaps 45 and 47 at the far and near ends thereof respectively. The terms far and near as just used have reference to relation of the gaps to the magnetron.

30 The piston is moved by means of a hollow screw 57 at the far side of the piston head from the magnetron and coaxial with and upon the end portion of the inner conductor which is at least in part within said hollow screw. Said hollow screw is longitudinally slotted as at 58a at opposite sides thereof and is held from rotation by alignment means such as transverse screws 58 which project into said slots. The hollow screw 57 projects from the end of the outer conductor and has a nut 59 on the projecting end, said nut being here shown as knurled for finger operation. The nut is rotatable but held from longitudinal displacement with respect to the said outer conductor by inclusion between portions of a bracket 60, one part of which is in the end of the said conductor and secured therein as by screw 61. Rotation of nut 59 will accordingly move the hollow screw longi-

tudinally, and as said screw is made fast to the piston head, said piston will be correspondingly moved. The arrangement likewise functions to hold the piston in a fixed position until an operator chooses to rotate the nut. Desired adjustment is thus effected by a simple and readily applied one-hand operation, and the setting made is retained until manually altered.

The center conductor 40 is composed of three sections; namely, at one end provides a section 62 having contact fingers, provides a middle section or rod 63, and provides at the other end an aligning sleeve 64. The purpose of the fingered section 62 is to provide, by splitting the section partway, a plurality of resilient fingers which will make firm mechanical and good electrical contact with the center conductor 37 of the magnetron output coupling 35. The aligning sleeve 64 has an annular channel 65 which, in conjunction with the other elements of center conductor 40, provides for a definite spacing of the glass seal 35a on the center conductor 27 from the ends of fingers 62, the spacing of which is relatively insensitive to frequency pulling of the magnetron compared to the position of the piston in the coaxial line. The length and position of the longitudinal slots in hollow screw 57 are chosen so that the cap 52 of the piston will not be able to reach or mechanically damage the glass seal 35a when moving the piston toward the glass.

The magnetron system described herein can be likened to a three-coupled circuit in which two are resonant cavities and the third a low Q coupling device. The properties of such a device can be derived on the basis of an orthogonal function method. The resonant cavities are those formed by the tuner line 66 and the magnetron cavities (which being tightly coupled are treated as a whole), and the low Q coupling device is comprised by coupling device 24 to the load. The frequency of the magnetron varies as the piston 41 is moved because the length of the line 66 introduces into the magnetron cavity for a given magnetron mode, an impedance which is in effect the equal of the ratio of the square of the product of the angular frequency and the mutual inductance and inversely as the impedance of the line 66. The orthogonal function method referred to adequately explains the repetitive characteristics of such a complex device.

I claim:

1. A magnetron having a series of tightly coupled cavities therein and having exterior tuning means operable over a wide band of frequencies, said tuning means comprising a coaxial line having a coupling loop within and midway of the length of and transverse to one cavity of said device, and a movable piston in said line movement whereof changes the reactance in the coaxial line and the impedance in the entire said series of cavities in the magnetron.

2. A magnetron having tuning means operable over a wide band of frequencies, said tuning means comprising a coaxial line coupled into the magnetron, said coaxial line providing inner and outer conductors, a movable piston in said coaxial line, and means constituting part of said piston but out of direct contact with and thereby forming gaps with said conductors and having a quarter-wave-length dimension from the gaps, which means presents a virtual short circuit across the gaps at all piston positions and sets up desired impedance to the magnetron.

3. A tuning means for a magnetron comprising a coaxial line having inner and outer conductors, a tuning piston in said outer conductor and girdling said inner conductor, said piston having a hollow screw projection from the outer conductor and receiving the inner conductor slidably therein, and a threaded member beyond the end of the outer conductor on said hollow screw rotatable thereon, and means in the path of and limiting axial displacement of said member whereby rotation of said member moves the screw and piston longitudinally.

4. A tuning means for a magnetron comprising a coaxial line having inner and outer conductors, means on the inner conductor locating the same at fixed longitudinal position with respect to the outer conductor, a tuning piston in said outer conductor and girdling said inner conductor, said piston having a hollow screw projecting from the outer conductor and receiving the inner conductor slidably therein, and a threaded member beyond the end of the outer conductor on said hollow screw rotatable thereon, and means in the path of and limiting axial displacement of said member whereby rotation of said member moves the screw and piston longitudinally.

5. A magnetron providing a series of resonant cavities tightly coupled electrically whereby the series oscillates as a single resonator at a frequency common to all said cavities, a cathode common to all of said resonant cavities, tuning means coupled into said resonator, an output means coupled in said resonator, said tuning means more closely following the contour of the resonator wall adjacent thereto and in closer proximity thereto and thereby being more tightly coupled electrically to the resonator than the output means, whereby pull of the tuning means on resonant frequency in the resonator exceeds pull of the output means thereon.

6. A magnetron providing a series of resonant cavities tightly coupled electrically whereby the series oscillates as a single resonator at a frequency common to all said cavities, a cathode common to all of said resonant cavities, tuning means having a loop in one of said cavities, output means having a loop in another of said cavities thereby coupling the output means in said resonator, and the loop of the tuning means having greater surface area in its cavity than surface area of the output loop in its cavity and more closely following the contour of the adjacent wall of its cavity and in closer proximity to said wall than said output loop thereby providing tighter electrical coupling of the tuning means to the resonator than the electrical coupling of the output means to the resonator, whereby pull of the tuning means on the resonant frequency in the resonator exceeds pull of the output means thereon.

7. A magnetron having an anode with radial vanes dividing the interior of the anode into a plurality of cavities radiating from a central cathode chamber, a cathode in said cathode chamber, exterior tuning means, and a loop in one of said cavities connected to said tuning means, said loop having a contour substantially the shape and size of the cross-section of the cavity in which located, at the plane of said loop, whereby the loop is in close proximity to the walls of the cavity for intercepting lines of force passing through said cavity and loop.

8. A magnetron having an anode with radial vanes dividing the interior of the anode into a plurality of cavities radiating from a central cathode chamber, said magnetron providing interac-

tion chambers at the ends of the cavities and cathode chamber, a strap electrically connecting alternate vanes at the ends thereof next one interaction chamber, and another strap at the same ends of the vanes electrically connecting the intervening vanes to each other, one of said straps being continuous and the other having a transverse break therein interrupting the circular series connection of the vanes by the strap having the break therein.

9. A magnetron having an anode with radial vanes dividing the interior of the anode into a plurality of cavities radiating from a central cathode chamber, said magnetron providing interaction chambers at the ends of the cavities and cathode chamber, pairs of straps at the ends of said vanes, one pair being in one interaction chamber and the other pair being in the opposite interaction chamber, and one strap of each pair electrically connecting alternate vanes at the ends thereof and the other strap of each pair electrically connecting the intervening vanes to each other, one strap of each pair being continuous and the other one of each pair having a transverse break therein interrupting the circular series connection of the vanes by the strap having the break therein.

10. A magnetron having an anode with radial vanes dividing the interior of the anode into a plurality of cavities radiating from a central cathode chamber, said magnetron providing interaction chambers at the ends of the cavities and cathode chamber, pairs of straps at the ends of said vanes, one pair being in one interaction chamber and the other pair being in the opposite interaction chamber, and one strap of each pair electrically connecting alternate vanes at the ends thereof and the other strap of each pair electrically connecting the intervening vanes to each other, one strap of each pair being continuous and the other one of each pair having a transverse break therein interrupting the circular series connection of the vanes by the strap having the break therein, one said break being at 90° rotated from the other.

11. A cathode comprising an externally emissive sleeve, a heater filament in said sleeve projecting from the ends thereof, washer-like disks at the ends of and transverse to the sleeve, an insulator inserted through one said disk and

5 having a portion in said sleeve, a long eyelet through the insulator projecting axially therefrom, and another eyelet telescoping on the projecting end of the first mentioned eyelet and secured thereto and fixing said eyelets to the insulator, and a lead-in connection secured to the outer telescoped eyelet.

12. A cathode comprising an externally emissive sleeve, a heater filament in said sleeve projecting from the ends thereof, washer-like disks at the ends of and transverse to said sleeve, an eyelet secured to one of said disks and to the filament, an input lead connected to said disk to which the eyelet is attached, an insulator inserted through the other disk and having a portion in said sleeve, a long eyelet through the insulator projecting axially therefrom, and a short eyelet telescoping on the end of the long eyelet projecting from the insulator and secured thereto, and a lead-in connection secured to the outer telescoped eyelet.
